UNITED STATES PATENT OFFICE.

GUY L. SPENCER, OF CLEVELAND, OHIO.

DESIGN FOR A RUBBER HEEL TREAD.

60,473.

Specification for Design.

Patented Feb. 21, 1922.

Application filed September 1, 1921. Serial No. 497,725. Term of patent 14 years.

To all whom it may concern:

Be it known that I, GUY L. SPENCER, a citizen of the United States, residing at Cleveland, county of Cuyahoga, and State of Ohio, have invented a new, original, and ornamental Design for Rubber Heel Treads, of which the following is a specification, reference being had to the accompanying drawings, forming part hereof.

In said drawing, Fig. 1 represents a plan view of a rubber heel showing my new design and Fig. 2 a sectional view corresponding to the line A—A of Fig. 1.

I claim:

The ornamental design for a rubber heel tread as shown.

GUY L. SPENCER.
